Robison W. Cassell

UNITED STATES PATENT OFFICE.

ROBISON W. CASSELL, OF TOLEDO, OHIO.

DESIGN FOR A GAME-BOARD.

SPECIFICATION forming part of Design No. 32,137, dated January 23, 1900.

Application filed December 20, 1899. Serial No. 741,066. Term of patent 3½ years.

To all whom it may concern:

Be it known that I, ROBISON W. CASSELL, a citizen of the United States, residing at Toledo, in the county of Lucas and State of Ohio, have invented and produced a new and original Design for a Game-Board, of which the following is a specification, reference being had to the accompanying drawings, which form a part hereof.

Figure 1 is a perspective view of the upper side of a game-board, showing my new design; and Fig. 2 is a similar view from below.

As shown in the drawings, my design consists of a square board 1, having rounded corners 2, the edges of which are surrounded by an upwardly-projecting flange 3, which fits snugly to the margin of said board 1 and extends a short distance above the upper surface thereof. A short distance inward from each edge of said board 1 and running parallel therewith is a heavy line 4, which lines extend entirely across said board and cross

each other a short distance from their ends. Grouped about the central portion of said board 1 are four holes 5, each of which holes 25 terminates below in the entrance to one of four small bags or receptacles 6, which are fastened to the under side of the board 1. The game-board is supported by four legs 7, inserted in the under side of the board 1, near 30 the corners thereof, as shown in Fig. 2.

Having described my invention, what I claim as new, and desire to secure by Letters Patent, is—

The design for a game-board, as herein 35 shown and described.

In testimony whereof I have signed my name to this specification in the presence of two subscribing witnesses.

ROBISON W. CASSELL.
